DESIGN FOR A PRESSURE GAUGE

Edward H. Wittenberg, Eau Claire, Wis., assignor
to National Pressure Cooker Company, Eau
Claire, Wis., a corporation of Wisconsin

Application June 24, 1943, Serial No. 110,512

Term of patent 7 years

To all whom it may concern:

Be it known that I, Edward H. Wittenberg, a citizen of the United States, residing at Eau Claire, county of Eau Claire, and State of Wisconsin, have invented a new, original, and ornamental Design for Pressure Gauges, of which the following is a specification, reference being had to the accompanying drawing, forming part thereof, and in which

Figure 1 is a side elevation of a pressure gauge showing my new design;

Figure 2 is a similar view looking at the gauge from a different angle; and

Figure 3 is a top view of Figure 1.

I claim:

The ornamental design for a pressure gauge, substantially as shown.

EDWARD H. WITTENBERG.
